BAR OF SOAP OR SIMILAR ARTICLE

Victor Koenigsberg, Franklin Square, N.Y., assignor to Colgate-Palmolive Company, New York, N.Y., a corporation of Delaware

Filed Mar. 9, 1967, Ser. No. 6,147

Term of patent 14 years

(Cl. D73—1)

FIG. 1

FIG. 2

FIG. 4

FIG. 1 is a perspective view of a bar of soap or similar article showing my new design;

FIG. 2 is a top plan view thereof;

FIG. 3 is a cross-sectional view taken on the line 3—3 of FIG. 2; and

FIG. 4 is a side elevational view thereof.

The bottom of the bar of soap is plain and unornamented.

I claim:

The ornamental design for a bar of soap or similar article, as shown and described.
